UNITED STATES PATENT OFFICE.

JAMES E. HAWKINS, OF GLENDALE, CALIFORNIA.

CAN-PUNCH.

1,338,300.

Specification of Letters Patent. Patented Apr. 27, 1920.

Application filed October 27, 1919. Serial No. 333,485.

To all whom it may concern:

Be it known that I, JAMES E. HAWKINS, a citizen of the United States, residing at Glendale, in the county of Los Angeles and 5 State of California, have invented certain new and useful Improvements in Can-Punches; and I do hereby declare the following to be a full, clear, and exact description of the invention, such as will 10 enable others skilled in the art to which it appertains to make and use the same.

The present invention relates to an implement for punching holes in cans or other containers of condensed milk, syrup or other 15 liquids, and aims to provide a novel and improved yet simple and inexpensive device for doing such work in a convenient and simple manner.

A further object is the provision of a can 20 punch which can be applied to cans of different sizes with equal facility.

Another object is the provision of such a device consisting of but two parts which can be inexpensively manufactured, and 25 which will nevertheless do its intended work in a practical and efficient manner.

With the foregoing and other objects in view, which will be apparent as the description proceeds, the invention resides in 30 the construction and arrangement of parts hereinafter described and claimed, it being understood that changes can be made within the scopes of what is claimed without departing from the spirit of the invention.

35 The invention is illustrated in the accompanying drawing, wherein:—

Figure 1 is a side elevation of the tool as applied to a small can, and

Fig. 2 is a similar view showing the device applied to a large can.

Fig. 3 is an elevation of the device in folded position, looking at right angles to the line of view of Figs. 1 and 2.

The device consists of two parts, a can-engaging member 1, and a punching or perforating lever 2. As shown, the member 1 is composed of a length of wire of suitable rigidity, which is doubled, so as to have the short arm 3 and the long arm 4 parallel 45 with one another. Bend 5 of the member 1 engages pivotally through an aperture 6 near one end of the lever 2; whereby to pivotally connect the member 1 and lever, permitting the lever to be swung on the bend 50 5 as a fulcrum. The lever can also be swung

between the arms 3 and 4, as seen in Fig. 3, to fold the device so that it can be conveniently stored away or carried. The end of the arm 3 is bent toward one side from the plane of the arms 3 and 4 to form a can-engaging hook or finger 7, and the end of the arm 4 is similarly bent toward the opposite side to form a can-engaging hook or finger 8. These hooks or fingers 7 and 8 are different distances from the bend 5 of the member 1, to engage cans of different sizes, as seen in Figs. 1 and 2. Thus, in placing one side of the member 1 against the can, the hook or finger 7 is adapted to engage the bottom or one end of the can, whereas when the opposite side of said member 1 is placed against the can, the hook or finger 8 is adapted to engage the bottom or the corresponding end of the can, permitting said member 1 to be reversed for small or large cans.

The end of the lever 2 adjacent to the bend 5 of the member 1 is provided with a pair of perforating or punching prongs 9 and 10, which are curved apart on divergent lines, so as to extend laterally in opposite directions. These prongs 9 and 10 are pointed so as to penetrate the top or corresponding end of the can. As shown, the lever 2 is stamped from sheet metal, although it may be made of wire or other suitable material, and the opposite end of the lever 2 has an aperture 11 for engaging a nail, hook or other member when it is desired to hang the device up.

In using the device on a small can, as seen in Fig. 1, the member 1 is placed against the can with the hook or finger 7 engaging the bottom or one end, and the lever 2 is swung to a position as illustrated, with the prong 9 ready to move toward and from the can. By swinging the lever 2 away from the member 1, this will force the prong 9 through the top or corresponding end of the can, making a perforation or slot of suitable size according to the amount that the lever 2 is moved, the metal being cut toward the side wall by the swinging movement of the prong 9. In applying the device to a large can, as seen in Fig. 2, the lever 2 is swung toward the opposite side so that when the member 1 is applied to the can with the hook or finger 8 engaging same, the prong 10 will be in a position to punch the hole in the opposite end of the can.

110

Having thus described the invention, what is claimed as new is:—

1. A can punch comprising a can-engaging member having opposite can-engaging hooks, and a lever pivotally connected near one end to said member and having opposite prongs to penetrate the can when said lever is swung relatively to said member.
2. A can punch comprising a can-engaging member and lever pivotally connected, said member having can-engaging hooks at different distances from the pivot to engage cans of different sizes, and the lever having means to penetrate the can.
3. A can punch comprising a can-engaging member and lever pivotally connected, said member having can-engaging hooks, at opposite sides and at different distances from the pivot to engage cans of different sizes, said lever having can-penetrating prongs extending in opposite directions to penetrate the can when said member and lever are reversed.
4. A can punch comprising a can-engaging member and a lever pivotally connected, said member having means on opposite

sides for engaging cans of different sizes, and the lever having means for penetrating the can when swung relatively to said member.

5. A can punch comprising a doubled can-engaging member having a bend and arms extending therefrom, said arms having can-engaging means, and a lever pivotally mounted on said bend, and having can-penetrating means.

6. A can punch comprising a doubled can-engaging member having a bend and arms of different lengths extending therefrom, the ends of said arms having hooks extending toward opposite sides for engaging cans of different sizes, and a lever pivotally mounted near one end on said bend and provided at said bend with can-penetrating prongs extending in opposite directions.

In testimony whereof I have signed my name to this specification in the presence of two subscribing witnesses.

JAMES E. HAWKINS.
